BOBBIN RECEIVER FOR LOOMS

Fredric E. Douglas, Hopedale, Mass., assignor to
 Draper Corporation, Hopedale, Mass., a corpora-
 tion of Maine

Application April 5, 1939, Serial No. 266,162

6 Claims. (Cl. 139—255)

The present invention pertains to ejected-bobbin receivers for bobbin changing looms, and more particularly relates to such receivers comprising a receptacle having a bobbin receiving apron therein.

Ejected-bobbin receivers of the type to which my invention applies commonly comprise a suitable receptacle, usually a can, which is positioned beneath the battery of a bobbin changing loom for receiving the empty bobbins which are ejected from the loom shuttle. The bobbins are ejected with such force that they may be splintered or otherwise damaged if they strike either the walls of the receptacle or the bobbins accumulated in the receptacle. This damage to the bobbins is particularly objectionable when weaving with rayon filling.

It has been proposed to prevent the aforementioned damage to the bobbins by providing the receptacle with a fabric apron for receiving and cushioning the impact of the ejected bobbins, and several constructions for accomplishing this purpose have been proposed. However, such prior proposed constructions have not been satisfactory and have not been used commercially to any appreciable extent. Objections to said proposed constructions are that they are expensive, require alteration of the receptacle to permit their installation, and seriously hamper the operation of emptying the receptacle.

A principal object of the present invention is to provide an ejected-bobbin receiver including a receptacle as aforesaid, a bobbin receiving apron comprising a frame covered with fabric 35 for receiving the impact of ejected bobbins, and suitable means for detachably securing only the upper edge of the apron to the front of the receptacle adjacent the top thereof, with the apron extending downwardly and rearwardly within 40 the receptacle; whereby such apron may be inexpensively constructed, may be readily attached to existing bobbin cans, and may be readily detached from such cans when the cans are to be emptied.

The foregoing and other objects of the invention are accomplished in the construction illustrated on the accompanying drawing, of which:

Fig. 1 is a view in perspective of part of a 50 bobbin changing loom having the preferred embodiment of my improved bobbin receiving receptacle associated therewith;

Fig. 2 is a view in elevation of said receptacle;

Fig. 3 is a side view of the same; and

Fig. 4 is a view of the improved bobbin receiv-

ing apron of Figs. 1-3, detached from the receptacle.

The loom shown on the drawing is generally of usual construction not of the present invention, and is accordingly but fragmentarily illustrated. The parts shown include a right hand loom side 1, the breast beam 2 at the front of the loom, the lay 3 having a shuttle box 4 at its right hand end, the shuttle 5 having a filling supply 6 therein, the right hand picker stick 7, 10 the chute or guide 8 for ejected bobbins, and transferring mechanism including the trans- 15 ferrer 9. It will be understood that the filling carriers comprise bobbins 10, and that an empty bobbin will be ejected down along the guide 8 each time a full bobbin is transferred to the shuttle, as is well known in the art.

A receptacle for receiving the ejected bobbins 10 is placed beside the loom side 1 underneath the guide 8. In the particular embodiment 20 shown, this receptacle consists of a conventional form of can 11 having the preferred form of my bobbin receiving apron therein. This can may be supported in proper position relative to the loom in any usual manner, not shown. The can 25 11 is a metallic receptacle having a bottom 12, front and rear walls 13 and 14, side walls 15, and an open top. The front wall 13 is extended upwardly and curled rearwardly to form a han- 30 dle 16.

The empty bobbins 10 are ejected with a force which is sufficient to damage the bobbins if they are allowed to strike against the walls of the can 11 or against other bobbins in the can. I accordingly provide the bobbin can with a bobbin receiving apron 17 for receiving the impact of the ejected bobbins, the apron being of a novel construction adapted to prevent the aforesaid damage of the bobbins. The preferred construc- 35 tion is also such that the bobbin receiving apron 40 may be readily attached to existing cans such as the can 11 and may be readily detached when the can is to be emptied.

The preferred bobbin receiving apron 17 shown comprises a frame 18, a fabric cover 19, and 45 attaching hooks 20. The frame 18 is preferably a light open rectangle of resilient metal, the construction being such that the apron is self-sus- taining as to shape but sufficiently resilient to yield under the impact of an ejected bobbin. The 50 cover 19 may consist of an envelope formed from canvas or the like, slipped over the frame 18 and fastened thereto as by rivets 21. The apron thus made is of substantially the same width as the bobbin can and is of the proper length to 55

extend from the top of the front wall 13 downwardly and rearwardly within the can and terminate short of the rear wall 14.

The top horizontal edge of the apron 17 is connected to the top part of the front wall 13 of the can by the hooks 20. As shown, these hooks are each attached to the frame 18 by a rivet or the like 22, the construction being such that the hooks are free to pivot on the rivets 22. The shape of each hook 20 is such that when the apron is attached to the can, the hook extends from its rivet 22 upwardly and outwardly of the can to the edge of the wall 13, thence forwardly around such edge, and thence inwardly along the wall 13. By merely turning the hooks 20 downwardly to the position shown by Fig. 4, the apron may be detached from the can.

The apron 17 is attached to the bobbin receiving can only by the hooks 20 located at the upper edge of the apron, the apron extending downwardly and rearwardly within the can 11 and being otherwise free and unsupported. Thus, the apron being resilient it yields under the impact of an ejected bobbin and thereby catches such bobbin and allows it to fall to the bottom of the can without damage.

Since the apron 17 is supported only by the hooks 20, it may be simply and cheaply constructed, and may be readily attached to existing bobbin cans without changing such cans in any way. Furthermore, the apron may be quickly detached from the bobbin can when the can is to be emptied.

Having fully disclosed the preferred embodiment of my invention, I claim:

1. An ejected-bobbin receiver for bobbin changing looms, comprising a receptacle having an open top for receiving ejected bobbins, a bobbin receiving apron comprising a resilient frame covered with fabric, and means for detachably securing the top of said apron to the front of said receptacle with the apron extending downwardly and rearwardly within said receptacle, said apron being otherwise free and unsupported whereby it may yield under the impact of an ejected bobbin.

2. An ejected-bobbin receiver for bobbin changing looms, comprising a receptacle having an open top for receiving ejected bobbins, a bobbin receiving apron comprising an open frame covered with fabric, and hooks at the upper edge of said apron for detachably connecting the apron to the upper part of the front of said receptacle, said apron extending from its upper edge downwardly and rearwardly within said receptacle in position to receive ejected bobbins.

3. An ejected-bobbin receiver for bobbin changing looms, comprising a receptacle having

an open top for receiving ejected bobbins, a bobbin receiving apron comprising a frame covered with fabric for receiving the impact of ejected bobbins, and hooks at the upper edge of said apron detachably connecting the apron to the top of the front part of said receptacle with the apron extending from its upper edge downwardly and rearwardly within said receptacle, said hooks comprising the sole means of attaching said apron to said receptacle whereby the apron may be readily removed when the receptacle is to be emptied.

4. An ejected-bobbin receiver for bobbin changing looms, comprising a receptacle having an open top for receiving ejected bobbins, a bobbin receiving apron comprising an open frame covered with fabric, said frame being sufficiently rigid to be self-sustaining but being sufficiently resilient to yield under the impact of an ejected bobbin, and hooks movably mounted on said frame at the upper edge thereof for detachably connecting said apron to the front of said receptacle adjacent the top thereof, said apron extending from its upper edge downwardly and rearwardly within said receptacle and being unsupported except at its upper edge as aforesaid.

5. An ejected-bobbin receiver for bobbin changing looms, comprising a can having walls and an open top for receiving ejected bobbins, a bobbin receiving apron comprising a substantially rectangular frame covered with fabric for receiving the impact of ejected bobbins, and hooks movably mounted on the upper edge of said frame for detachably connecting said apron to the top part of the front wall of said can, said apron extending from its upper edge downwardly and rearwardly within said can, and said hooks comprising the sole means of attaching said apron to said can whereby the apron may be readily removed when the can is to be emptied.

6. An ejected-bobbin receiver for bobbin changing looms, comprising a can having walls and an open top for receiving ejected bobbins, a bobbin receiving apron comprising a substantially rectangular frame covered with fabric, said frame being self-sustaining but sufficiently resilient to yield under the impact of an ejected bobbin, and hooks pivoted to the upper edge of said frame for detachably connecting said apron to the top part of the front wall of said can, said apron extending from its upper edge downwardly and rearwardly within said can and being unsupported except at its upper edge as aforesaid, said hooks comprising the sole means of attaching said apron to said can whereby the apron may be readily removed from the can when the latter is to be emptied.
